SUCTION CLEANER

Harry B. White, Canton, Ohio, assignor to The Hoover Company, North Canton, Ohio, a corporation of Ohio

Application August 3, 1933, Serial No. 683,419

11 Claims.

(Cl. 15—183)

The present invention relates to suction cleaners in general and particularly to a new and improved rotary agitator construction for a suction cleaner. More specifically the invention comprises the provision of an improved adjustable height brush construction in a rotary agitator for a suction cleaner.

It is an object of the present invention to provide a new and improved adjustable brush construction in a rotary agitator for a suction cleaner. It is another object to provide, in a rotary agitator for a suction cleaner, a reversible brush which is designed to co-operate with its seat in the agitator body so that its height above the agitator surface is changed when the brush is reversed end for end. Still another object is the provision, in a rotary agitator for a suction cleaner, of a screw-held brush which extends to different heights above the surface of the agitator when the brush is reversed end for end. These and other more specific objects will appear upon reading the following specification and claims and upon considering in connection therewith the attached drawing to which they relate.

In the drawing, in which a preferred embodiment of the invention is disclosed:

Figure 1 is a side view, partly in section, of a modern suction cleaner with the agitator constructed in accordance with the present invention embodied therein;

Figure 2 is a side elevation, partly in section, of the agitator constructed in accordance with the present invention with the brushes positioned in the low positions;

Figure 3 is a section through one of the brush seats in the agitator with the brush positioned in the high position;

Figure 4 is a partial section through the agitator looking in the direction of the arrows upon the line 4—4 of Figure 3;

Figure 5 is a section upon the line 5—5 of Figure 3;

Figure 6 is a view in perspective of a brush element constructed in accordance with the present invention removed from the agitator.

The modern suction cleaner incorporates both suction and positive beating means. The positive beating means are normally provided in the form of a rotary agitator which includes both a rigid surface-contacting element and a removable brush or brushes. The rigid element is not affected by wear in its contact with a surface covering and so requires no adjustment. The brush elements, however, wear down so that they require adjustment. If the brush elements do

not extend as far radially as the rigid beating elements, they fail to accomplish their function. In the present invention a new brush element is provided which co-operates in a new and novel manner with its seat in the agitator body so that after the brush has been used in the agitator for a time and the length of the bristles has been decreased through wear, it is possible to reverse the brush end for end in its seat in the agitator resulting in a greater extension of the brush bristles beyond the said surface through positioning the back of the brush higher in its seat.

Referring again to the drawing a modern suction cleaner is shown comprising a nozzle 15 which is interiorly connected to the fan chamber 2. A rotary fan 3, driven by an unshown motor within the motor casing 4, creates a reduced pressure within the fan chamber which functions to draw air between the lips 5 and 6 into the nozzle 1, through the fan chamber 2 and exhaust it through the exhaust outlet 7 into a detachable dust bag 8. The cleaner is movably supported upon front and rear wheels 9 and 10 respectively, there being provided a pivoted handle 11 by which the operator may propel the machine. Within the nozzle 1 and positioned so as to contact the surface covering between the lips 5 and 6 is positioned a rotary agitator indicated generally by reference character 12. Agitator 12 comprises an elongated cylindrical body 13 which is provided substantially centrally of its length with a reduced portion 14 which functions as a pulley to receive the driving belt 15 connected to the pulley 16 at the lower end of the driving motor shaft. End cups 17, 17 close the ends of the cylindrical body 13 and seat upon bearings 18, 18, the inner races of which are mounted upon the longitudinally extending through supporting shaft 19 which extends completely through the cylindrical body. The outer ends of the shaft 19 are threaded and each seats a plate member 20 which is flanged at its periphery and overlies the end of the body 13 to function as a thread guard and prevent the accumulation of foreign matter about the supporting bearing 18.

The elements which accomplish the positive beating function comprise rigid bars 21, 21 positioned upon the periphery of the agitator body and extending longitudinally and helically thereon. These beater elements extend to a definite height above the agitator body and impart to the surface covering, in the operation of the machine, a positive beating action. Their height is

not affected by wear and they extend throughout their life to substantially the same radial distance beyond the normal surface of the agitator body 13.

To co-operate with the positive beating elements 21, 21 brushes 22, 22 are provided which comprise rigid backs 23, 23 in which are mounted brush bristles 24. It is desirable that the bristles 24 extend above the normal surface of the agitator body to a height which is substantially equal to the height of the beater elements 21, 21. It is also desirable, however, that the bristle length be sufficiently great that reasonable flexure and bending is possible. To insure this flexibility it is necessary to mount the rigid back of the brush below the normal surface of the agitator body. This is done in open bottom seats 25, 25. The sides of these seats are formed by folding inwardly the wall of the body 13 adjacent thereto. The ends are formed to receive and seat the ends of the brush back 23. The inner or pulley end of each seat is provided by an inserted stamping or end member which is suitably secured in place as by welding its sides to the elongated sides of the seat. Each end member comprises an inwardly extending bottom shoulder or ledge 27, a second shoulder or ledge 28 positioned thereabove and of lesser and longitudinal length, an upper shoulder 26. A block of resilient material such as rubber 29 is carried by the end member, the shoulder 28 extending therethrough.

The outer end of each seat 25 is formed by an inwardly extending shoulder 30 formed on a metallic plate 31 carried by the inner side of the end cup 11. Shoulder 30 is positioned radially out- 35 side of shoulder 27 at the opposite end of the brush seat as is clearly seen in Figure 3.

The ends of the rigid back 23 of the brush are formed in a very definite manner to co-operate with the shoulders at the ends of the brush seat. 40 The normal plane of the bottom of the brush back 23 is indicated by the reference character B. Near one end of the back is positioned a shoulder C which is at a lower level than the normal bottom B. At the opposite end of the brush and above the normal bottom B is found a shoulder D. At the first end of the brush and outside of the portion forming the low shoulder C is found a third shoulder E. The height of shoulder E above shoulder D is equal to the height of shoulder D above shoulder C. Shoulder C is formed on the brush back so that when the brush is positioned as shown in Figure 3 it will rest upon the relatively long shoulder 27. With the brush reversed, as shown in Figure 2, however, shoulder 45 C is completely inside of the supporting shoulder 30 so that the shoulder E supports the brush back. At one end of the brush the height of the back is the distance from shoulder C to the top of the back at its end and is equal to the distance between shoulders 26 and 27 of the brush seat. At 50 the other end the back height is measured from the shoulder D to the top of the back at its end and is equal to the distance between the shoulders 27 and 28.

55 Referring to Figure 2 in particular the brush is shown positioned within its seat in the agitator in the low position, or that position in which it would be placed when the brush was new. Shoulder D rests upon supporting shoulder 27 at the 60 inner end of the brush and the back extends under shoulder 28. At the opposite end of the brush shoulder E rests upon the supporting shoulder 30, the relation between shoulders 27 and 30 being such that the brush is parallel to the longitudinal 65 axis of the agitator.

Referring to Figure 3 in particular it is seen that the brush has been reversed in its seat and shoulder D now rests upon outer shoulder 30. As shoulder D is lower on the brush back than shoulder E it is clear that the brush at that end of the back extends further beyond the surface of the agitator than before. As the shoulder D is lower on the brush back than shoulder E it is clear that the brush bristles at the outer end of the agitator extend beyond their first position relative to the 10 agitator surface a distance which is equal to the difference in height between the shoulder D and the shoulder E. At the inner end of the brush it is seen that the lowest shoulder C is now supported by the supporting shoulder 27 and the end 15 of the brush back underlies the shoulder 28. As shoulder C is lower than shoulder D on the brush back by exactly the same distance that shoulder D is lower than shoulder E it is apparent that the inner end of the brush bristles has been raised 20 above the agitator surface to a distance equal to that found at the outer end. The brush is therefore in its high or worn position.

To secure the brush within its seat in either of its two positions a screw 32 is provided at the 25 outer end of each brush seat which is threaded into the agitator body thickened at that point by a guard member 33 which is formed integrally thereon. At each end of the brush back 23 is formed an outwardly and downwardly inclined 30 recessed shoulder F which, when the brush back is positioned in the seat, partially underlies the end of the screw. The surface of each shoulder F is inclined so that as the screw advances downwardly in the agitator into contact with the face 35 F the brush back will be forced by a cam action inwardly and toward the center of the agitator body. The opposite end of the brush back is forced into contact with the resilient rubber pad 29 at the inner end of the seat which resistingly 40 holds the brush against the screw and in place.

With the brush positioned in its low position it is seen that the inner end of the brush back contacts the pad 29 between the shoulder 27 and the shoulder 30. With the back in its upper or worn 45 position, as shown in Figure 3, it is seen that the brush back contacts the pad both above and below the shoulder 28, the brush back above the shoulder E being provided with a recessed portion indicated by the reference character 35 which accommodates the inwardly extending shoulder 28.

To remove the brush from its seat it is only necessary to unscrew the screw 32 so that the brush back can be moved longitudinally outward so that the inner end thereof is disengaged from 55 under an overlying shoulder. With the brush in the low or new position this overlying shoulder is the shoulder 28. With the brush in the high or worn position it is the shoulder 26.

I claim:

1. In a rotary agitator for a suction cleaner, a body, an elongated seat in said body, a brush including a rigid back having bristles therein, said seat overhanging one end of said back, means resiliently urging said back toward the opposite end of said seat, and a manually adjustable screw carried by said body and adapted to contact said back at a point spaced from said end and at an angle to oppose the movement of said brush by said means and prevent the outward displacement of said brush, said screw being adjustable to a position to permit the sliding of said back thereunder to permit the disengagement of the opposite end thereof.

2. In a rotary agitator for a suction cleaner, a 75

- body, an elongated seat in said body, a brush including a rigid back having bristles therein, said seat overhanging one end of said back, and a manually adjustable screw carried by said body and extended into said seat into contact with a cam surface on said back at the opposite end thereof to force said back under the overhanging portion of said seat and oppose its outward displacement at said point of contact.
10. 3. In a rotary agitator for a suction cleaner, a body, an elongated seat in said body, a brush including a rigid back having bristles therein, said brush reversibly seating in said seat, said seat being formed to overhang said brush at one end, downwardly facing shoulders at different heights on said back adapted to support said brush in said seat, said seat being provided with upwardly facing shoulders at spaced points adapted to cooperate with the shoulders on said back, and manually adjustable locking means securing said back in said seat and forcing it under said overhanging portion of said seat.
4. In a rotary agitator for a suction cleaner, a body, an elongated seat in said body, a brush including a rigid back having bristles therein, said brush reversibly seating in said seat, said seat overhanging said brush at one end, inwardly facing shoulders at different heights on said back at the ends thereof, outwardly facing shoulders of different heights at the ends of said seat adapted to cooperate with said first-mentioned shoulders to support said back at different heights in the reversed positions, and a manually adjustable locking member at one end of said seat preventing the displacement of said back outwardly from said seat and from under the overhanging portion thereof.
5. In a rotary agitator for a suction cleaner, a body, an elongated seat in said body, a brush including a rigid back having bristles therein, said back being of different effective heights at its opposite ends, means at one end of said seat at different heights adapted to overlie and prevent the outward displacement from said seat of either end of said back, means at different heights in said seat adapted to support said back at its ends, and a manually rotatable screw overlying the end of said back spaced from said overlying means exerting a force to secure said back in said seat and under said overlying means.
6. In a rotary agitator for a suction cleaner, a body, an elongated seat in said body, a brush including a rigid back having bristles therein, said seat being formed with longitudinally spaced outwardly facing supporting shoulders at different heights therein, said back being formed with spaced inwardly facing supporting shoulders at different heights thereon, said back being reversible in said seat, different pairs of shoulders cooperating to position said back in the reversed positions, stationary means at one end of said brush to overlie the back and prevent its displacement at that point in either position, and adjustable means carried by said body and extended into said seat into contact with said back securing said back under said stationary means and preventing its displacement from said seat at its point of contact therewith, characterized by the fact that said manually adjustable means are movable to a position to permit said back to move from under said stationary means.
7. In a rotary agitator for a suction cleaner, a body, an elongated seat in said body, a brush including a rigid back having bristles therein, said seat being formed with spaced outwardly facing supporting shoulders at different heights thereon, said back being formed with spaced inwardly facing supporting shoulders at different heights thereon, said back being reversible in said seat, different pairs of shoulders cooperating to position said back in the reversed positions, stationary means at one end of said brush to overlie the back and prevent its displacement at that point in either position, and adjustable means carried by said body and extended into said seat into contact with said back securing said back under said stationary means and preventing its displacement from said seat at its point of contact therewith, characterized by the fact that said manually adjustable means comprises a screw positioned at the end of said back which is adjustable to a position out of contact with said back thereby permitting said back to be moved to disengage it from under said stationary means.
8. In a rotary agitator for a suction cleaner, a body, an elongated seat in said body, a brush including a rigid back having bristles therein, outwardly facing supporting shoulders at the opposite ends of said seat at different heights therein, inwardly facing supporting shoulders at the opposite ends of said back separated in height thereon by a distance equal to that separating the shoulders on said seat, a second shoulder at one end of said brush separated in height from said first-mentioned shoulder at that end by twice the height difference between said shoulders on said seat, said brush being reversible in said seat to provide different bristle projection therefrom, and means to removably secure said brush back in said seat.
9. In a rotary agitator for a suction cleaner, a body, an elongated seat in said body, a brush including a rigid back having bristles therein, supporting shoulders at the opposite ends of said seat at different heights therein, one of said shoulders extending farther into said seat than the other, vertically and longitudinally spaced shoulders at one end of said back, a shoulder at the opposite end of said back having a height midway between said shoulders at the one end of said back, the shoulders on said back being arranged to contact selectively the shoulders on said seat, characterized by the fact that the upper shoulder on said back supports one end thereof in one position when opposite the short seat shoulder while the lower shoulder supports the same end in the reversed position when opposite the long seat shoulder, means being provided to prevent the outward displacement of said back from said seat in both positions.
10. A removable brush element for a suction cleaner agitator comprising a rigid back having bristles therein, said back being provided with a downwardly facing supporting shoulder at one end, a downwardly facing supporting shoulder on the opposite end of said back at a higher level thereon, a third downwardly facing shoulder on said back positioned between the two first-mentioned shoulders at a lower level than said first-mentioned shoulder, characterized by the fact that the level of said first-mentioned shoulder is midway between the levels of the remaining shoulders.
11. In a rotary agitator for a suction cleaner, a body, an elongated seat in said body, a brush including a rigid back having bristles therein, brush-positioning means vertically and longitudinally spaced on said back, brush-positioning means vertically and longitudinally

spaced in said seat, said brush being reversibly positioned in said seat, said brush-positioning means selectively cooperating to position said brush at different heights in said body in the reversed positions, characterized in that stationary means overlie one end of said brush back in said seat, a manually operable retractable member

overlying the opposite end of said back, said stationary means and said manually operable retractable member cooperating to prevent displacement of said brush from said seat and to hold said brush-positioning means on said back and on said seat in cooperative relationship.

HARRY B. WHITE.
